WINDING MACHINE

Reginald O. Eaton, Erie, and Ethan Vars, Lawrence Park, Pa., assignors to General Electric Company, a corporation of New York

Application June 8, 1931. Serial No. 542,888

23 Claims. (Cl. 153—64.5)

Our invention relates to winding machines, more particularly to machines for winding coils of a resilient material, and has for its object the provision of an improved winding machine of this character.

Our invention, although not limited thereto, is especially applicable to the winding of ribbon or strip-like, metallic resistance materials edge-wise into elliptical coils, such as are used in certain electrical apparatus and applications.

Considerable difficulty has been experienced heretofore in attempting to make edge-wise-wound coils of ribbon-like resilient materials, especially coils of elliptical form, by reason of the inherent tendency of each turn of the material when wound to spring back toward the position it had before being formed. This tendency in some cases is particularly pronounced, and at times causes the successive turns of the coil to form in a spiral. In order to remove the spiral it is necessary to resort to rather expensive and troublesome operations.

Our invention in one of its aspects contemplates the provision of an improved apparatus for winding coils whereby the turns of the coils are formed into bends having an arc somewhat greater than the arc it is intended they shall assume in the finished coil so as to compensate for the inherent tendency of the material to spring back after the turns are formed.

In carrying our invention into effect in one form thereof, we provide a winding arbor and a rotatably mounted winding head operably associated with the arbor. Mounted on the winding head is a suitable jaw member arranged to grip the material fed to the winding head so that the material is turned about the arbor by rotation of the head. The winding head is controlled to bend each turn of the material through an arc somewhat greater than the arc it is intended that the turn shall assume in the finished winding so as to compensate for its tendency to spring back. Means are provided for feeding suitable lengths of the material to the winding head whereby the bends or turns are formed at the proper points to form a coil of the desired shape.

We further provide, in one form of our invention, suitable power means for operating the winding head and the material feeding means, and also for operating certain other auxiliary apparatus used in our machine, and provide suitable controlling means for the power operating means whereby the operation of the machine is essentially automatic.

For a more complete understanding of our invention reference should be had to the accompanying drawings, in which Fig. 1 is a plan view of a winding machine embodying our invention; Fig. 2 is a diagrammatic view of the machine of Fig. 1 and illustrating certain control members and circuits arranged in accordance with our invention; Fig. 3 is a perspective view of a portion of the winding machine of Fig. 1, parts being shown in section so as to illustrate more clearly certain details of construction, and certain portions being broken away; Fig. 4 is a fragmentary side elevation of the winding machine of Fig. 1 and illustrating the positions certain of the elements have at one stage of the winding operation; Fig. 5 is a view similar to Fig. 4 but illustrating the positions certain of the elements have at a more advanced stage of the winding operation; Fig. 6 is a vertical section taken through the line 6—6 of Fig. 4; Fig. 7 is a view similar to Figs. 4 and 5 but illustrating the positions certain of the elements have at a still more advanced stage of the winding operation; Fig. 8 is a sectional view taken through the line 8—8 of Fig. 6 and Fig. 9 is a view similar to Fig. 8 but illustrating certain elements of the machine in different operative positions.

Referring to the drawings, we have shown our invention in one form in connection with a winding machine for winding elliptical coils formed of flat, ribbon-like, resilient, metallic material wound edge-wise. While coils intended to be used in various services and applications may be formed with our machine, we have illustrated the machine as applied to the winding of coils intended to be used for electrical purposes, such as resistance elements.

In one form, our invention comprises a winding head 10 rotatably mounted in a supporting base or standard 11. As shown, the winding head is of substantially cylindrical form and is provided with journals 10a and 10b at its end portions arranged to rotate in corresponding bearings 12 provided in the base. Suitable lubricating devices 13 are provided to lubricate these bearings.

The winding head is rotated by means of a rack 14 arranged to reciprocate in a retaining guideway 15 provided for it in the base 11. This rack, as shown, meshes with a gear 16 surrounding the winding head substantially at its central portion and secured for rotation with the head. The gear 16 may be secured to the wind-

ing head in any suitable manner, as for example by means of a key 17 (Fig. 6).

One end of the winding head is recessed, as indicated at 18, and in a portion of this recess 5 is arranged a plate 20 formed of some suitable relatively hard material, such as tool steel. This plate, as shown, is of segmental shape and has an area substantially equal to the area of the recessed portion. Within the segment of the recess left by the plate 20 is arranged a second segmental plate 21, this plate also being formed of some suitable relatively hard material, such as tool steel. Secured to the second plate and preferably formed integrally with it is a third 10 plate 22. This plate is provided with an arm 23 extending somewhat beyond the adjacent edges of the recess and winding head, as clearly 15 shown in Figs. 3, 4, and 5. The plates 20 and 21 may be secured to the winding head in any 20 suitable manner, but preferably will be secured thereto by means of screw fastening means 24.

Arranged on an axis substantially coincident with the axis of rotation of the winding head 10 is a winding arbor 25. This arbor, as shown 25 (Fig. 6), is secured in a central aperture 26 provided for it in the plate 20. It is about this arbor that the turns of the coil are wound.

The material 27 to be wound, which material is shown to be of ribbon-like form, is fed by 30 suitable means to the winding head from a supply spool 28 rotatably mounted on a base or support 30 provided for the entire machine. The material feeding means comprises a feeding plate 31 arranged for reciprocatory motion to 35 and from the winding head in suitable guides 32 provided for it in the base 11. The guide-ways 32, as shown, are of limited length, and the length of the path of motion of the plate 31 in these guides may be adjusted by means 40 of a suitable adjusting stop member 32a. The feed plate, as shown, is provided with a pair of vertically spaced laterally projecting arms 33. The material 27 is fed to the winding head between these arms, and the arms carry a suitable 45 clamping device for securing the material to the plate, whereby when the plate is moved forward in its cross-head the material will be carried with it and thus fed to the winding head.

50 This clamping device, as shown, comprises a clamping member 34 pivotally mounted on an eccentric 35 which in turn is rotatably mounted in the projecting arms 33. The position of the eccentric in the arms is adjusted by means of a lever 36 which, as shown, is secured to turn the eccentric in its bearings. This lever is formed as a yoke and may be locked in any suitable position of adjustment by means of a locking stud 37 threaded in the upper arm 33 55 and passed through an arcuate slot 38 provided for it in the yoke. As is well understood, if the stud be turned in so that it engages the yoke the latter will be locked, whereas if the stud be turned out the yoke will be released 60 to permit adjustment of the eccentric.

The clamping member is provided with a jaw 40 (Figs. 1, 2, and 3) secured therein and 65 formed of some suitable relatively hard material, such as tool steel. This jaw is so arranged in the clamping member and the latter is so arranged on its eccentric that if the clamping member be rotated on the eccentric in a clockwise direction, as viewed in Figs. 1, 2, and 3, the jaw will grip the material 27 and clamp it securely against the feeding plate 31; these

members are further arranged so as to automatically release the material if the material be pulled forward toward the winding head independently of the feeding device or if the feeding device be moved back toward its initial feeding position, or in other words; its position remote from the winding head. The degree of pressure with which the jaw engages the material is adjusted by means of the eccentric 35. It will be observed in view of the foregoing arrangement that when the feeding plate is in its initial feeding position, shown in Figs. 3 and 4, that if the jaw be moved to grip the material and the plate then be moved forward to its position adjacent the winding head a predetermined length of the material will be fed to the winding head, this length being determined by the length of the path of movement of the feeding plate and hence by the adjustment of the screw 32a. It will also be observed that when this operation has been completed if the material be moved forward relatively to the plate or if the plate be moved backwardly toward its initial position relative to the material, the jaw will automatically be released to free the material of the feeding device.

It is to be noted that the feeding device is so arranged that it will feed the material 27 to the winding head on one side of the winding arbor 25, as for example the upper side, as viewed 105 in the figures.

Suitable means are provided on the winding head for gripping the material fed to it, whereby when the head is rotated in a clockwise direction, as viewed in Figs. 3, 4, 5, and 7, the material will be wound about the winding arbor 25 so as to form one turn of the winding. This gripping means comprises a clamping member 41 provided with a jaw 41a on one of its ends. This clamping member, as shown, is of rod-like 115 form and is mounted to slide in a hole 42 provided for it through the winding head and arranged so that when the head is in its initial winding position, shown in Figs. 3, 4, and 7, the jaw will receive the material 27 beneath it, the material thus being sandwiched between the jaw and the hardened plate 20 carried by the winding head. As shown, the clamping member is arranged to slide in fixed bearings 43 and 44 provided in the end portions of the bore 42. 125 Arranged in the bore 42 and surrounding the clamping member is a suitable compression spring 45 having one end bearing on the bushing or bearing 43 and its other end bearing on a collar 46 secured to the clamping member. By 130 reason of this arrangement the jaw is biased by the force of the spring to its releasing position, that is, to a position at which the material is free to pass beneath it. The jaw is moved to its clamping position by means of a lever 135 47. This lever, as shown, is provided with a forked end and is pivotally secured to the end of the clamping member, which is opposite the jaw 41a and which projects from the winding head, by means of a pin 48 so that the clamping member is received between the arms of the fork. As shown, the fork arms have curved or cam-like surfaces 47a arranged to bear against a hardened plate or washer 50 carried by the bushing 43. As is well understood, if the lever 145 be rotated on its pin from the solid line position of Fig. 1 to the dotted line position of this figure the cam surfaces of the lever will engage the plate 50 so as to move the jaw 41a toward the winding head against the bias of the spring 150

45; and also when it has thus been rotated to move the jaw to its clamping position it will automatically lock itself with the jaw in its clamping position by reason of the shape given 5 to the cam surfaces 47a. To release the jaw, it is necessary to return the lever 47 to its solid line position of Fig. 1; this movement of the lever, of course, allows the spring 45 to move the jaw to its releasing position. It is to be 10 noted that the clamping member has a segmental cross section, the flat portion bearing on the upper edge of the plate 20, as shown in Fig. 6, to prevent rotation of the clamping member and jaw relative to the winding head. It 15 will be observed in view of the above described jaw arrangement, that when the jaw is in its clamping position it will securely lock the material to the winding head, whereby when the latter is rotated the material will be bent around 20 the winding arbor.

In order to prevent the length of the material 27 adjacent the winding head and arbor from buckling during the bending operation, a suitable retaining device is provided. This device 25 comprises a sizing plate 51, a pressure applying plate 52 and a clamping plate 53 arranged to secure the sizing and pressure plates to the base standard 11 of the machine. The sizing plate 51, as shown, is arranged to bear on a substantially flat surface provided for it on the standard, while the pressure plate 52 is sandwiched between the sizing plate and the clamping plate. As shown, the standard is provided 30 with a plurality of locking members 54 projecting from its surface, and the sizing plate 51 is provided with a pair of tongues 51a and 51b received in the recesses defined by the locking members, whereby the plate is securely locked in position on the base. The plate 52 likewise is 35 provided with a pair of ears 52a and 52b which are received between these projecting locking members so as to lock this plate in position. The clamping plate is secured over the other two plates by means of three studs 55 which are 40 passed through the clamping plate so as to be received in the projecting portions 54, while all of the plates are further secured to the base by means of a bolt 56 which is passed through 45 apertures provided in the plates and received in the base.

The sizing plate 51, as shown, has a considerable length, and a width substantially equal to the width of the ribbon-like material 27 being wound (Fig. 6). The lower surface of this sizing plate bears directly on the upper surface of the material passing beneath it. The pressure plate 52 bears against the side area of a substantial length of the material fed to the winding head, and projects downwardly for a considerable distance below the path of movement of the material. The pressure plate is forced against the side of the material 27 which is being fed to the winding head by means of a suitable pressure device which applies pressure at the lower end of the plate to force it inwardly toward the winding head. This movement of the plate is permitted by reason of the fact that the plate is supported at its upper end and has sufficient resiliency to permit it to be drawn toward the plate by the pressure device. This pressure device comprises a suitable operating member 60 which, as shown, is of rod-like form and which is passed through a central aperture 61 provided for it in the winding head and a similar aperture provided in the arbor 25. One end of this rod is passed through an aperture provided for it in the lower end of the pressure plate and carries a collar 62 bearing against the plate. The opposite end of this rod passes through a bushing 63 provided on the winding head. It will be observed that if the pressure rod be moved inwardly of the winding head, that is, toward the left, as viewed in Fig. 6, the pressure plate will be drawn inwardly against the portion of the ribbon in the winding head. If the force which is applied to draw the rod 60 inwardly be released the pressure plate by reason of its inherent resiliency will spring out to release the ribbon. The pressure plate together with the sizing plate effectively prevent buckling of the ribbon during the winding operation.

It is preferable that the length of the material 27 directed from the supply spool 28 to the feeding device be placed under a slight tension. This is accomplished by means of a pressure device arranged to apply pressure to that portion of the material between the feeding device and supply roll. This pressure device comprises pressure plates 64 and 65 arranged to 50 clamp the material between them. The plate 64, as shown, is rigidly mounted on the base 11 on one side of the path of movement of the material, while the plate 65 is mounted for movement toward and away from the plate 64 on the opposite side of this path of movement. The plate 65 is mounted on one end of an actuating rod 66 which is slidably mounted in a supporting frame 67 attached to the base 11. This frame comprises two spaced upright arms 68 provided 55 with apertures 70 (only one of which is shown) in which the rod is slidably received. Interposed between the outer arm 68 and a nut 71 threaded on the rod intermediate its ends is a compression spring 72 preferably surrounding 60 the rod. It will be observed that the tension of this spring applies a force to the rod tending to move the plate 65 toward its cooperating plate 64 so as to apply a pressure to the ribbon 27 lying between the plates. This, of course, applies a tension to the ribbon as it is being drawn toward the winding head by the feeding device. The pressure plate 65 is drawn to release the material 27 by means of a lever 73 provided with a forked end that is pivotally secured to the 65 outer end of the rod 66 and arranged as shown to engage the adjacent arm 68 when the arm is raised from its dependent position, shown in Fig. 3, to its extended position, shown in Fig. 1, to withdraw the rod and plate 65. Preferably, 70 the plates 64 and 65 will be formed of a relatively hard material, such as tool steel.

It will be understood that in the operation of the machine thus far described, the feeding device with the ribbon 27 clamped to it will be moved forwardly toward the winding head so as to feed thereto a predetermined length of the ribbon. During this operation, as has been pointed out, the plates 64 and 65 will be in position to apply a suitable tension to the ribbon. After the ribbon has been fed to the winding head, the jaw 41a will be operated to clamp it to the head and the head will be rotated by means of its rack 14. During this operation the feeding device clamping jaw 40 will be released, in a manner which has been described previously, and the feeding plate will be returned to its initial position. The winding head will be rotated through an arc to bend the material about the arbor 25. This arc is determined by the 75

arm 23 which is carried by the segmental plate 21, and by a pair of associated stop members. The plates 51, 52, and 53 constitute the first stop member and define the initial or starting position of the winding head. The second stop is adjustable and comprises a rod 74 provided in a support 75 fastened to the base 11. This rod is provided with handle means 76 whereby its position can be adjusted. It will be observed (Fig. 5) that the stop is mounted in the path of movement of the arm 23 so as to permit the winding head to rotate a distance sufficient to bend the material 27 through an arc somewhat greater than the arc it is intended the bend 10 shall assume in the finished winding so as to compensate for the inherent tendency of the resilient material to spring back toward its original position. In the case illustrated, that is, when an elliptical coil is being formed, the stop 15 will be adjusted so as to permit the head to bend the material about the arbor through an arc somewhat greater than 180°, the arc of motion, of course, being determined by the resilient characteristics of the material being wound.

25 As the winding head is rotated to bend the material, the material will gradually be drawn forwardly by the motion of the winding head under the sizing plate 51 and through the pressure plate 52, this motion of the material being permitted because the feeding device will have been released. During the bending operation, the jaw 41a will effectively grip the material to carry it around with the head, while the sizing and pressure plates will effectively prevent buckling of that portion of the ribbon adjacent to 30 and being bent around the arbor.

35 After the head has been rotated through the desired arc of motion, which arc will be determined by the stop 74, the jaw 41a and the pressure plate 52 will be released and the winding head will be returned by its rack 14 to its initial position, shown in Fig. 3; the clamping member 34 will then be operated to again grip the material to the feeding device which will then 40 be moved forward to feed another length of the material to the winding head after which another turn will be formed, as was the previous turn.

45 The pressure plate 52 has an additional function, viz., to automatically strip or remove the turns as they are wound. As shown, the lower edge of this plate is provided with a cam-like surface 77 arranged so that as the winding head is rotated to form successive bends or turns, the 50 formed turns, as they are rotated by the winding head in its operation in forming another turn, will engage the stripper cam surface 77 and will automatically wind themselves outwardly from the winding head. The wound turns 55 thus fed outwardly are received on a suitable stationary supporting member 78.

60 It is to be noted that the straight lengths of material fed to the winding head and the size of the turns formed by the winding arbor determine the lengths of the short and long axes of the elliptical turns. These, of course, may be varied by changing the length of travel of the feeding plate and by substituting winding arbors having different diameters. If turns of 65 larger or smaller diameter be desired it is merely necessary to provide arbors having the appropriate diameter. Also arbors of different lengths will be provided so as to accommodate materials of various thicknesses; and likewise, various 70 sizing plates 51 will be provided to accommodate 75

materials having different widths and thicknesses.

It is also to be understood that coils can be formed in our machine having different shaped turns merely by adjusting the arc through which 80 the winding head is rotated and by adjusting the feed of the feeding devices.

The feeding plate 31, the feeding clamping member 34, the winding head clamping jaw 41a, the clamping pressure plate 52 and the winding head all are automatically operated through successive cycles of operation, each cycle including the steps above described. To effect this, the various elements of the machine are provided with fluid actuating motors. As shown, 90 the winding head actuating rack 14 is connected directly to the piston rod 80a of a fluid actuating motor 80 provided for the winding head; and the feeding plate 31 is connected to the piston rod 81a of a fluid actuating motor 81 by 95 means of a lever 82 pivoted intermediate its ends and secured at one end to the piston rod and at its opposite end to the feeding plate. These two motors, it will be observed, are arranged to be operated in both directions by fluid under 100 pressure. The clamping member 34 of the feeding device is arranged to be operated to its clamping position with the feeding plate in its initial feeding position, i. e., its position remote from the winding head, by means of a fluid 105 motor 83; this motor is mounted on the base 11 and is so arranged that its piston rod 83a when moved forwardly from its cylinder engages the clamping member 34 to clamp the ribbon to the feeding plate. The actuating 110 stroke of this motor is effected by means of fluid admitted to the motor cylinder under pressure, while the idle stroke of the motor is effected by means of a compression spring 83b arranged, as shown, under the piston and between the piston and the adjacent cylinder head. The jaw clamping member 41 is moved to its clamping position (shown in dotted lines in Fig. 1) by means of a fluid motor 84 and is operated, 115 as will be pointed out in greater detail herein- 120 after, to its releasing position (shown in solid lines in Fig. 1 and in dotted lines in Fig. 2) by means of a fluid motor 85. The piston rod 84a of the motor 84 is arranged to directly engage the operating lever 47 provided for the jaw 125 to apply the jaw, while the piston rod 85a of the motor 85 is arranged to engage the lever 47 to release the jaw through the medium of a pivoted lever 86. These motors 84 and 85 are similar in their construction to the motor 83 130 in that their actuating strokes are effected by means of fluid admitted to their cylinders under pressure, while the idle strokes are effected by springs 84b and 85b. The pressure plate 52 is operated to its pressure applying position by 135 means of a fluid motor 87, the piston rod 87a of which is connected through the medium of a pivoted lever 88 to the actuating rod 60 provided for the pressure plate. This motor is substantially identical in its construction to the motors 140 83 and 84.

145 These fluid motors are provided with suitable valve control means whereby the fluid under pressure for operating the motors is suitably controlled.

The rack or winding head actuated motor 80 is controlled by means of a valve mechanism 90 comprising a main valve 91. This valve is provided with an inlet manifold 92 shown in section in Fig. 2 as two chambers; it is to be 150

understood, however, that the inlet manifold is a single chamber. The left-hand end of the cylinder of the motor 80 communicates with the intake manifold through a pipe 93 and a chamber 94, while the right-hand end of the cylinder 80 communicates with the intake manifold by means of a chamber 95 and a conduit 96. This valve mechanism further comprises a pair of valves 97 and 98, the valve 97, as shown, controlling a port between the chambers 92 and 94 and also a port between the chamber 94 and the atmosphere, and the valve 98 controlling similar ports arranged in the chambers 92 and 95. Spring means are provided normally biasing these valves to close communication between the chamber 92 and the chambers 94 and 95. The stems of these valves project from the valve casing and are arranged to be operated by a lever 100 pivotally mounted at its center and arranged to be operated somewhat like a walking beam so that when operated to one position, shown in Fig. 2, it will actuate the valve 98 to provide communication between the chambers 92 and 95 and thus admit fluid under pressure from the manifold 92 to the right-hand end of the cylinder of the motor 80, whereas if it is operated in the opposite direction it will operate the valve 97 to connect the chambers 92 and 94 and allow the valve 98 to close; this operation, it will be observed, connects the left-hand end of the motor cylinder to the supply manifold and allows the right-hand end to exhaust to the atmosphere through the open chamber 95.

It will be observed that the conduit 96 is provided with two branches 96a and 96b shunting each other. Within the conduit portion 96b is arranged a stop cock or valve 96c, while in the portion 96a is arranged a check valve 96d arranged to close against pressure in the cylinder 80. A valve 93a, similar to the valve 96c is arranged in the conduit 93. These valves are provided to control the speed of the fluid motor 80.

It is essential in some cases in order to prevent breakage of the material fed to the winding head that the winding head be moved at a controlled uniform speed. This is effected by means of the valves. In the operation of this portion of the mechanism, it will be understood that the stop cocks 93a and 96c will be adjusted so that the proper speed is obtained in the power stroke, that is when the piston is being forced from left to right. During this movement of the piston the air on its right side is caused to exhaust through the stop cock 96c arranged in the conduit 96b because the conduit 96a will be closed by the check valve 96d. This causes a back pressure on the right side of the piston and causes the piston to move at a uniform speed. However, on the return stroke of the piston, air will be allowed to pass freely through the check valve into the right hand end of the cylinder so as to cause the return stroke to be effected at a considerably higher speed than the power stroke.

The main valve mechanism is operated by means of a pilot valve mechanism 101. As shown, the operating lever 100 of the main valve is provided with an actuating motor 102, fluid being controlled to the opposite ends of the cylinder of this motor by means of the pilot valve mechanism. This pilot valve mechanism comprises an intake manifold 103 which is connected through conduits 104 and 105 to the opposite ends of the motor cylinder 102. These conduits are controlled by means of valves 106 and 107.

These valves, as shown, control ports between the intake manifold and the conduits 104 and 105 leading to the ends of the cylinder, and also control ports between these conduits and the atmosphere. The valves 106 and 107 are arranged to be operated by a pivotally mounted lever 108 similar to the lever 100 for operating the main valves. In this case, however, the lever is operated in its one direction by a tension spring 110 and is operated in its opposite direction by means of an electromagnet 111. This magnet is sufficiently strong when energized to attract the arm 108 against the force of the spring 110, whereas when it is deenergized the lever will be actuated by the tension of the spring. It will be observed that when either of these valves is open to provide communication between the intake manifold and its associated controlled end of the cylinder of the valve motor 102, its associated port communicating with the atmosphere will be closed, while the other valve will close the opposite end of the cylinder to the intake manifold and will open it to the atmosphere. In this manner the fluid supplied to the motor 102 for operating the main valve is controlled.

A suitable source of fluid supply 112, such as air under pressure, is controlled by a valve 113 and communicates with the intake manifold 92 of the main valve by means of a conduit 114 and with the intake manifold 103 of the pilot valve by means of conduits 115, 116, and 117, as clearly shown in Fig. 2.

The valve 118 for controlling the fluid motor 81 is an ordinary piston valve controlling conduits 120 and 121 communicating with the opposite ends of the motor cylinder. The space between the piston valve heads is supplied with air under pressure through the conduit 115 and a conduit 122, while the opposite ends of the valve cylinder communicate with the atmosphere through exhaust conduits 123. The piston valve is biased by means of a spring, as shown, toward the lower end of its cylinder, i. e., to a position for admitting air to the motor 81 cylinder to actuate the motor 81 to return the feeding plate to its initial feeding position, and is provided with an electromagnet 124 arranged when energized to move the valve to the upper end of its cylinder to admit air to the motor 81 to cause a feeding stroke of the feeding plate.

The valve mechanism 125 for controlling the fluid supplied to the motor 83 to cause an actuating stroke thereof is of the piston type and controls a pair of passages 126 and 127 communicating with one end, the upper end, of the cylinder 83. Fluid is supplied to the valve chest of this valve mechanism by means of the fluid conduit 116, and as shown, the valve is biased to its lower position, as shown in Fig. 2, by means of a spring so as to cut off the intake 116. In this position of the valve, however, the upper end of the cylinder of the motor 83 communicates with an exhaust passageway 128 through the conduit 126. The valve is arranged to be actuated to the other end of its cylinder by means of an electromagnet 130. It will be observed that when the valve moves to this end of the cylinder the upper end of the motor cylinder will be closed to the exhaust 128, while the valve will open communication between the intake conduit 116 and the upper end of the cylinder through the conduit 126. This operation of the valve effects an actuating stroke of the motor. When the valve is returned to its lower

position, the upper end of the cylinder is opened to the exhaust 128, thereby allowing the motor to be actuated by the spring 83b arranged below the piston.

5 The motors 84, 85, and 87 are provided with valve mechanisms 131, 132, and 133 similar in construction to the valve mechanism 125 provided for the motor 83. The motor 84 is supplied with fluid under pressure through the conduits 115, 134, and 135, while the motor 85 is supplied directly from the conduit 115, and the motor 87 through the conduits 115, 134, and 136.

10 The energizing circuits of the above-described valves are controlled to effect a predetermined sequence of operation of the motors which they control, and hence of the elements controlled by the motors so that the above-described cycle of 15 operation of the machine is effected. This sequence of operation is effected by means of a switch 140 which is arranged to be actuated to its closed position by a latch element 140a carried by the piston rod 81a of the feeding device motor 81; a switch 141 mechanically connected with the switch 140 through the medium 20 of a link 142 and arranged to be closed in response to the operation of the motor 84 in applying the jaw 41a, and switches 143 and 144, the former being arranged to be operated by an actuating member 145 carried by the winding 25 head actuating rack 14 and the latter to be operated by the rack. The switch 141 is provided with a latching device 146 arranged to lock it in its closed position. This latching device is operated to its releasing position by the operation 30 of the motor 85 in releasing the jaw 41a through the medium of a link 147 connected to the latch and with the pivoted lever 86.

35 The electromagnetically operated valves are provided with a suitable source of electrical supply 40 150 controlled by a main switch 151.

45 It is believed that a description of the operation of the apparatus as a whole will clarify the operation of the valves and their associated motors. A complete description of the operation of the winding machine will, therefore, be given at this point. Let it be assumed that the main air valve 113 has been opened to admit air under pressure to the system and that the controlling switch 151 has been closed to connect the energizing circuits of the electromagnetically operated valves to the electrical supply source 150. Referring more particularly to the diagrammatic view shown in Fig. 2, it will be observed that when the switch 151 is closed, a circuit will be completed for the electromagnet 124 of the valve 118 provided for the motor 81 from the lower conductor of the supply source 150, through the switch 151, the closed switch 144 which will be held closed by the rack 14, it being understood 50 that the rack will be in the position shown in Fig. 2 at the beginning of the winding operation, and thence through the operating coil of the electromagnet 124 to the upper conductor of the supply source. The energization of this circuit 55 operates the valve to admit air to the left-hand end of the cylinder of the motor 81. In response to this operation, the motor moves the feed slide 31 from its position shown in Fig. 4 toward the left to feed a predetermined amount of the material 27 to the winding head; it will be understood that at some time previous to this operation, the clamping member 34 of the feed device will have been operated to clamp the material to the feed slide. During this operation of the 60 motor 81 the actuating element 140a will be carried

65 toward the right, as viewed in Fig. 2, and will engage the switch 140 to close it. It will be observed that this switch is allowed to close independently of the connected switch 141 by reason of a slotted connection 152 provided between the link 142 and the switch 140. It will be observed that when this switch closes it completes an energizing circuit for the electromagnet of the valve 131 provided for the motor 84. This operation admits air under pressure to the upper end of the cylinder of the motor 84 which thereupon 70 operates the clamping lever 47 to move the jaw 41a to its clamping position. The clamping lever 47 in being moved to its clamping position, shown in dotted lines in Fig. 1, engages the actuating element of the switch 141 to close this switch, the switch then being held in its closed position by the latch 146. As the switch 141 is being closed, the link 142 will operate the switch 140 to its open position, thereby effecting a de- 75 energization of the valve 131. This operation allows the air which has been admitted to the motor 84 to be exhausted to the atmosphere, thereby allowing the piston rod 84a to be retracted for the next operation of this motor. 80

85 The switch 141 in closing completes energizing circuits for the valve 133 provided for the motor 87 and for the electromagnet 111 provided for the valve mechanism of the motor 80. The valve mechanism 133 in response to its energization causes air to be admitted to the motor 87 which then operates through the lever 88 and actuating member 60 to cause the clamping plate 52 to apply pressure to the length of material 27 adjacent the winding arbor. The electromagnet 110 90 111 in being energized causes the valve 101 to connect the lower end of the cylinder of the main valve operating motor 102 with the supply manifold 103, while the opposite end of this cylinder is connected to the atmosphere through the conduit 104. The motor 102 operates the main valve mechanism to connect the left-hand end of the cylinder of the motor 80 with the supply manifold 92 and the right-hand end of this cylinder with the atmosphere. The motor 102 95 in response to this operation of its valve moves the operating rack 14 toward the right, as viewed in Fig. 2, which operation causes the winding head to move in a counter-clockwise direction from the position shown in Fig. 4 to 100 the position shown in Fig. 5. This operation of the winding head bends the material 27 around the winding arbor and through an arc which is 105 determined by the setting of the stop member 74. 110

115 As the rack 14 starts to move toward the right to effect the above described winding operation, the switch 144 is allowed to open, thereby effecting a deenergization of the electromagnet 124 provided for the valve 118 of the feeding plate motor 81. This operation admits air under pressure to the right-hand end of the motor cylinder and as a result the feeding plate is returned to its initial position, shown in Figs. 2 and 4. It will be observed, therefore, that as the winding head starts to rotate, and consequently starts to draw the material 27 forwardly from the feeding plate, the feeding plate practically simultaneously therewith is caused to move backwardly toward its initial position. These two operations, as has been pointed out, contribute to effect an automatic release of the clamping member 34. 120

125 As the winding head completes its winding stroke, that is, as it arrives at the stop 74, as shown in Fig. 5, the member 145 carried by the rack will engage the switch 143 to close it. 130

This operation of the switch 143 completes energizing circuits for the operating coil 130 of the valve 125 provided for the motor 83 and the operating coil of the valve 132 provided 5 for the motor 85. The valve 125 thereby is operated to admit air under pressure to the motor 83 which operates to apply the clamping jaw 34 to the material 27 to again lock it to the feeding plate. The energization of the valve 132 10 allows air under pressure to be admitted to the motor 85 which is operated to force the lever 86 into engagement with the clamping lever 47, which has been rotated by the winding head to the dotted line position shown in Fig. 2, 15 and from its position shown in Fig. 3 to its position shown in Fig. 9. The motor 85 moves the lever 47 a sufficient distance to release the jaw 41a.

The lever 86 in being moved to release the 20 jaw 41a also releases the latch 146 so as to allow the switch 141 to open. This operation of the switch effects a deenergization of the operating coil of the valve 133 provided for the pressure plate operating motor 87 and the electromagnet 111 provided for the valve mechanism of the winding head operating motor 80. The valve 133 in operating in response to its 25 deenergization allows the air which has been admitted to the cylinder 87 to effect the application of the pressure plate 52 to exhaust to the atmosphere, whereby the piston 87a is retracted and the pressure plate released. The deenergization of the electromagnet 111 causes air under pressure to be admitted to the right-hand end of the cylinder 80, while the air which has been previously admitted to the left-hand side of this cylinder is exhausted. It 30 will be observed by reason of the above described operations that the winding head first will be caused to disengage the material which has been wound and then will be returned from the position shown in Fig. 5 to its initial winding position shown in Fig. 4.

The motor 80 in returning the winding head 35 to its initial position, moves the rack 14 toward the left thereby allowing the switch 143 to open. The switch 143 in opening effects a deenergization of the operating coils of the valves of the motors 85 and 83. This allows the motor 85 to 40 return the actuating lever 86 to its initial position, shown in Fig. 2, and likewise allows the piston of the motor 83 to return to its initial position, shown in Fig. 2. When the rack arrives at the left hand end of its stroke, as 45 shown in Fig. 2, in other words, when the winding head has been returned to its initial position, shown in Figs. 3 and 4, the switch 144 will again be closed so as to reenergize the circuit for the electromagnet 124 provided for the valve 50 of the feeding plate motor 81. This operation, as before, causes this motor to operate the feeding plate in its feeding direction toward the winding head. The motor 81 in thus operating the feeding device recloses the switch 140 to effect 55 the operation of the motor 84 to apply the jaw 41a to the material fed to the winding head, and so on, the above-described cycle of operation is repeated until the desired number of turns have been formed. Fig. 7 illustrates the 60 winding head in position to form a turn, and the position the wound coil assumes at this stage of the winding operation. It will be understood that during the winding operation the turns as they are formed will wind themselves outwardly on the receiving rod 78 by reason of

the fact that they will successively engage the stripper cam surface 77 provided on the pressure plate 52.

In order to stop the operation of the machine, it is merely necessary either to close the main 80 valve 113 or to open the switch 151.

By suitably adjusting the stop member 74 in accordance with the resilient characteristics of the material being wound, each turn of the winding will be bent through an arc somewhat greater than the arc it is intended it shall assume in the finished coil so as to compensate for the spring back tendency of the material. Thus, the material will be bent through such an arc that when the material springs back the straight lengths of the ellipse will be formed parallel to each other and the longitudinal axes of the turns will lie in the same plane.

While we have shown a particular embodiment of our invention, it will be understood, of course, that we do not wish to be limited thereto since many modifications may be made, and we, therefore, contemplate by the appended claims to cover any such modifications as fall within the true spirit and scope of our invention.

What we claim as new and desire to secure by Letters Patent of the United States, is:

1. A machine for bending resilient materials and the like comprising a winding arbor, a rotatable winding member for bending said material about said arbor, means for feeding said material to said winding member, means on said winding member for gripping said material to said member, means for applying and releasing 105 said gripping means and means for moving said winding member and controlling the motion thereof whereby said material is turned through an arc substantially greater than the arc through which it is desired to bend said material so as 110 to compensate for the inherent tendency of said material to spring back toward its original position.

2. Apparatus for winding resilient materials and the like into a coil comprising an arbor, a 120 movably mounted winding head operably associated with said arbor, means for feeding said material to said winding head, clamping means on said head for engaging said material to wind it about said arbor by the movement of said 125 head, means imparting motion to said head to wind said material about said arbor through an arc greater than the arc through which it is desired to form each turn of said coil so as to compensate for the inherent tendency of said 130 material to spring back toward its original position, and interlocking means between said feeding means, said clamping means and said means for imparting motion to said head so that said members are operated in a predetermined 135 sequence.

3. Apparatus for winding resilient materials and the like into a coil comprising a winding arbor, a winding head, means mounting said winding head for rotation about an axis substantially coincident with the axis of said arbor, means for feeding said material to said winding head in substantially equal increments, jaw means on said head for clamping said material thereto, and means for rotating said head 145 through an arc greater than the arc through which it is desired to form each turn of said coil so as to compensate for the inherent tendency of said material to spring back toward its original position.

4. A coil winding machine comprising a winding head, means mounting said winding head for rotation on a substantially fixed axis, a winding arbor operably associated with said winding head, means for feeding the material to be wound to said winding head in substantially equal increments, means on said head for engaging said material to wind it about said arbor as said head is rotated, stop means controlling the arc of movement of said head, motive means for rotating said head and operating said feeding means, means controlling said motive means so as to effect a predetermined sequence in the operation of said winding head and said feeding means and means jointly responsive to the operation of said feeding means and said winding head controlling said engaging means on said head to engage and release said material. 80
5. A coil winding machine comprising a winding head, means mounting said winding head for rotation, means for feeding the material to be wound to said winding head in substantially equal increments, means on said head for clamping said material, means for rotating said head through a determined arc of motion, means jointly responsive to the operation of said feeding means and said means for rotating said head controlling the operation of said clamping means to clamp and release said material, a winding arbor operably associated with said head, whereby said material is turned about said arbor when said head is rotated through said arc of motion and means for removing the turns automatically as they are wound. 95
6. Apparatus for winding ribbon-like resilient materials and the like edge-wise into a coil comprising a winding head, means mounting said head for rotation, means for rotating said head back and forth through a determined arc of motion, means for feeding said material to said head in substantially equal increments, jaw means on said head arranged to grip said material fed to said head and clamp it to said head, means for tensioning the length of material fed to said head, a winding arbor operably associated with said head so that said material is turned about said arbor when said head is turned in one direction through its arc of movement and guiding means for the material fed to said head arranged to prevent buckling of said material during the winding operation. 110
7. A machine for winding resilient materials and the like into a coil comprising a winding arbor, a winding head operably associated with said winding arbor, means for rotating said winding head through a predetermined arc of motion, feeding means for said material comprising jaw means arranged to grip said material and means for moving said jaw means to feed said material to said winding head in substantially equal increments, jaw means on said winding head for gripping the material fed to said head so as to clamp it to move with said head through its arc of movement whereby said material is turned about said winding arbor, said feeding jaw means being arranged to automatically release said material at the start of the winding movement of said head and means automatically releasing said winding head jaw means when said winding head has been moved through its winding arc of movement. 125
8. Apparatus for winding ribbon-like resilient materials and the like edgewise into a coil comprising a winding arbor, a winding head, means mounting said winding head for rotation on an axis substantially coincident with the axis of said winding arbor, power operated means for rotating said winding head, means for feeding said material to said winding head in substantially equal increments comprising a feeding plate, means mounting said feeding plate for reciprocatory motion toward and away from said winding head, power operated means for reciprocating said plate, jaw means for gripping said material to said plate and power operated means for applying said jaw means, second jaw means carried by said winding head for gripping the material fed thereto whereby as said head is rotated said material is wound about said winding arbor, power means for operating said second jaw means to grip said material, and also to release said material upon the completion of the winding motion of said winding head and power operated means for confining the length of material fed to said head whereby it is prevented from buckling during the winding operation. 90
9. Apparatus for winding resilient metallic materials and the like into a coil comprising a winding arbor, a winding head, means mounting said winding head for rotation on an axis substantially coincident with the axis of said winding arbor, power operated means for rotating said winding head, means for feeding said material to said winding head in substantially equal increments comprising a feeding plate, means mounting said feeding plate for reciprocatory motion toward and away from said winding head, power operated means for reciprocating said plate, jaw means for gripping said material to said plate and power operated means for applying said jaw means, second jaw means carried by said winding head for gripping the material fed thereto whereby as said head is rotated said material is wound about said winding arbor, power means for operating said second jaw means to grip said material, and also to release said material upon the completion of the winding motion of said winding head, and control means for establishing a predetermined sequence in the operation of said power operated means. 100
10. A coil winding machine comprising a winding member, a fluid motor for operating said winding member to effect a winding operation and for returning said member for a subsequent winding operation and means controlling said fluid motor so that said winding member is moved at a substantially uniform speed when effecting a winding operation and is returned at a higher rate of speed. 115
11. A coil winding machine comprising a movably mounted winding head, means for feeding the material to be wound to said winding head, a fluid motor connected to operate said winding head and means controlling the motion imparted to said winding head by said fluid motor. 130
12. A coil winding machine comprising a rotatably mounted winding head, means for feeding the material to be wound to said head in substantially equal increments, means on said head for engaging a portion of the material fed thereto to move said portion with said head as the head is rotated, a winding arbor operably associated with said winding head so that the material moved with said head is turned about said winding arbor, a fluid motor for operating said head and adjustable stop means for limiting the arc through which said fluid motor operates said winding head. 140
13. A coil winding machine comprising a rotatably mounted winding head, a winding arbor 150

- operably associated with said head, means for rotating said winding head, means for feeding the material to be wound to said winding head, means on said head arranged to engage the material fed thereto so that as said head is rotated said material is wound about said arbor and interlocking control means between the means for rotating said winding head and said feeding means for establishing a predetermined sequence of operation between them. 10
14. Apparatus for winding coils and the like comprising a rotatably mounted winding head, a winding arbor operably associated with said head, a fluid motor for rotating said head, a feeding device for feeding the material to be wound to said head in substantially equal increments, a fluid motor for operating said feeding device, electromagnetically operated valves controlling said fluid motors, switch means controlling said electromagnetically operated valves and means controlling said switching means in accordance with the operations of said motors so as to effect a predetermined sequence of operation between said motors. 15
15. A machine for winding edge-wise wound coils of ribbon-like resilient material comprising a winding arbor, a winding head, means mounting said head for rotation on a fixed axis substantially coincident with the axis of said arbor, a gear arranged to rotate with said winding head, a rack meshing with said gear, a fluid motor connected to operate said rack whereby motion is imparted to said winding head, a jaw member carried by said head for movement to a position adjacent said head and to a position remote from said head, fluid motors arranged to operate said jaw between said positions, a feed plate for said material mounted for movement toward and away from said winding head, said feed plate comprising jaw means arranged to engage said material and move it toward said winding head as said plate moves toward said head and to release said ribbon automatically upon opposite relative movement between said ribbon and said feed plate, a fluid motor controlling the operation of said second jaw means to grip said ribbon, a fluid motor connected to operate said feed plate toward and away from said winding head, a clamping plate arranged to be pressed against the area of a substantial length of said material passed to said winding head to prevent buckling of said material while being turned about said arbor, a fluid motor connected to force said plate against said material, electromagnetically operated valves controlling the fluid supplied to said fluid motors, switching means for controlling the energizing circuits of said electromagnetically operated valves and means operated by certain of said fluid motors for controlling said switching means to effect a predetermined sequence of operation between said motors. 20
16. A machine for winding ribbon-like resilient, metallic materials and the like into elliptical edge-wise wound coils comprising a winding arbor, a winding head rotatable on an axis substantially coincident with the axis of said arbor, a fluid motor mechanically connected to rotate said winding head about its axis, means for feeding the material to be wound to said head comprising a feeding plate, means mounting said feeding plate for reciprocatory motion between a position remote from said head to a position adjacent said head, a second fluid motor mechanically connected to reciprocate said feeding plate, a member carried by said plate arranged in one position of said member to clamp said material to said plate whereby as said plate is moved from its remote position to its position adjacent said winding head a predetermined length of said material is fed to said winding head and a third fluid motor arranged to operate said clamping member to clamp said material to said plate when said plate is in its said remote position, said clamping member being automatically released upon the occurrence of an opposite relative movement between said plate and said material, a jaw movably mounted on said winding head between a position to clamp said material to said head and a releasing position, a fourth fluid motor arranged to operate said jaw to its clamping position when said winding head is in its initial winding position and a fifth fluid motor arranged to effect a release of said jaw when said winding head is in the final position after a turn has been formed, a plate arranged to bear on the area of a substantial portion of the length of said material fed to said head so as to prevent said material from buckling during the winding operation, a sixth fluid motor mechanically connected to apply a pressure to said clamping plate to bear on said length, means dependent upon the operation of said second fluid motor in moving said feeding plate to its position adjacent said winding head for effecting the operation of said fourth fluid motor to apply said winding head jaw to clamp said material to said head, means dependent upon this operation of said fourth fluid motor for effecting the operation of said sixth fluid motor to apply said pressure plate and also to effect the operation of said first fluid motor to rotate said head to wind the material about said arbor, means dependent upon the operation of said first fluid motor in rotating said head to wind said material for effecting the operation of said second fluid motor to return said feeding plate to its remote position, and upon said winding head arriving at its said final winding position for effecting the operation of said fifth fluid motor to release said winding head jaw and for effecting the operation of said third fluid motor to apply the feeding plate clamping member to said material, and means dependent upon the operation of said fifth fluid motor in releasing said jaw for effecting the operation of said sixth fluid motor to release said pressure plate and for effecting the operation of said first fluid motor to return said winding head to its initial winding position, means dependent upon the operation of said first fluid motor in returning said winding head to its initial position for effecting the operation of said second fluid motor to operate said feeding plate to feed said material to said winding head. 25
17. A machine for winding resilient materials and the like comprising a winding arbor, a winding head operably associated with said winding arbor, means for rotating said winding head, feeding means for said material comprising clamping means arranged to grip said material and means for moving said clamping means to feed said material to said winding head in substantially equal increments, clamping means on said head for gripping the material fed to said head so that it is moved with said head about said winding arbor, means responsive to the operation of said feeding means for applying said second named clamping means to grip said material and means responsive to the operation of 30

said winding head for releasing said second named clamping means to release said material and for applying said first named clamping means to grip said material.

- 5 18. A machine for winding resilient materials and the like comprising a winding arbor, a winding head operably associated with said winding arbor, means for rotating said winding head, means for feeding said material to said winding head, means for clamping said material to said head, means for operating said clamping means to clamp and release said material and means responsive to the operation of said clamping means controlling said operating means for rotating said head to initiate the operation of said head when said clamping means is operated to clamp said material to said head.

- 10 19. A machine for winding resilient materials and the like comprising a winding arbor, a winding head operably associated with said winding arbor, means for rotating said winding head, means for feeding said material to said winding head, means for clamping said material to said head, means for operating said clamping means to clamp and release said material, means responsive to the operation of said clamping means controlling said operating means for rotating said head to initiate the operation of said head when said clamping means is operated to clamp said material to said head and means responsive to the operation of said head for operating said clamping means to release said material after a turn has been wound.

- 15 20. A machine for winding resilient materials and the like comprising a winding arbor, a winding head operably associated with said winding arbor, means for rotating said winding head, feeding means for said material comprising clamping means arranged to grip said material and means for moving said clamping means to feed said material to said winding head in substantially equal increments, clamping means on said head for gripping the material fed to said head so that it is moved with said head about said winding arbor, means responsive to the operation of said feeding means for applying said second named clamping means to grip said material, means responsive to the operation of

said second named clamping means to grip said material controlling the head rotating means to initiate the operation thereof to rotate said head, means responsive to the operation of said head for releasing said second named clamping means when a turn has been wound and for initiating the operation of said head rotating means to return said head to its initial winding position and means responsive to the operation of said winding head to said initial position controlling said feeding means to effect the operation thereof to feed another increment of material to said winding head.

- 20 21. A machine for winding resilient materials and the like comprising a winding arbor, a winding head operably associated with said winding arbor, means for rotating said winding head, means for feeding material in substantially equal increments to said head, means for operating said feeding means, means for clamping said material to said head and for releasing it, operating means for said clamping means and interlocking means between said operating means for said head, said feeding means and said clamping means for establishing a predetermined sequence of operation between them.

- 25 22. A machine for winding resilient materials and the like comprising a winding arbor, a winding head operably associated with said winding arbor, means for rotating said winding head, means for feeding said material to said head, jaw means on said head arranged to grip said material to said head, means for operating said jaw means to grip and release said material, a clamping plate operably associated with said head so as to apply pressure to the length of material supplied to said head to prevent its buckling during the winding operation, means for operating said plate to clamping and releasing positions, means responsive to the operation of said jaw means to grip said material controlling said clamping plate operating means to move said plate to its clamping position and means responsive to the operation of said winding head controlling said operating means to release said clamping plate when a turn has been wound.
